UNITED STATES PATENT OFFICE.

FRANZ BOLLHORN, OF VEDDEL, NEAR HAMBURG, GERMANY.

AERIAL SHIP.

No. 904,930.

Specification of Letters Patent.

Patented Nov. 24, 1908.

Application filed June 27, 1907. Serial No. 381,146.

To all whom it may concern:

Be it known that I, FRANZ BOLLHORN, a subject of the King of Prussia, and resident of No. 14 Am Bahndamm, Veddel, near 5 Hamburg, in the Empire of Germany, master mariner, have invented a new and useful Aerial Ship, of which the following is a specification.

The present invention relates to an improved aerial ship, which is primarily 10 destined for military purposes but which may also be employed for transport, sport and recreation.

Special objects of the invention are to simplify and cheapen the construction, and to 15 render more efficient, serviceable and durable in operation aerial ships of the nature set forth.

With these ends in view the invention consists in the novel combination, arrangement 20 and adaptation of parts, all as more fully hereinafter explained, shown in the accompanying drawings, and then specifically set out in the appended claims.

25 In the drawings, which illustrate, by way of example, one mode of carrying out the invention, Figure 1 shows an inverted plan view of the improved aerial ship, Fig. 2 shows a side elevation of the improved aerial 30 ship, the chamber in the lower portion of the balloon body, which houses the paddle wheel as well as the car, which carries the driving means being represented in a vertical sectional view, Fig. 3 shows a cross sectional view through the improved aerial ship illustrating the driving means, and Fig. 4 shows, on a larger scale, a detail of construction.

The aerial ship employs a balloon body made up by two hollow chambers 1 and 3, 40 which are destined for the reception of a charge of hydrogen—or other suitable gas. The forward chamber 1 is provided at its front with a conical or pointed end 2, so that the smallest possible resistance will be offered to the air. The rear chamber 3 of the balloon body is considerably longer than the fore part 1, but the fore part 1 is much wider in cross section and extends lower down than the rear part 3. Both chambers 45 50 1 and 3 of the balloon body have the same

or approximately the same cubical capacity. The construction and shape of the balloon body not forming part of my invention, I wish to point out that modifications may be carried out in that respect. 55

In the lower portion of the balloon body described is provided a space or chamber 4 closed on top and at the sides, but open towards the bottom, within which the driving means are to be located. 60

For driving the aerial ship, I employ a pair of paddle wheels 7, 7 of known construction fitted with paddle sails 8 and housed in the space 4. Said wheels 7, 7 are keyed on a shaft 9 that is rotatably journaled in proper bearings carried in the space 4. The shaft 9 is driven by the intermediary of known transmission means from any suitable source of motive power, preferably an internal combustion engine 10 carried by and fittingly mounted in the car 11. 65 70

The sail wheels 7, 7 consist each of two cross frames secured in coinciding positions on the shaft 9. At the external ends 12 of the corresponding arms of the wheel frames 75 are pivotally supported axles 13 which carry the frames 14 holding the sails 8 more or less tensioned.

The driving means are adapted to impart a planetary motion to the paddle sails in regard to the shaft 9, that is to say, while being rotated around the common axis 9 the sails 8 simultaneously revolve around the axes 13, for the purpose of holding them radially directed only in their lowermost position as is already known in connection with aerial ships. The planetary motion of the sails 8 around the pivots 13 is attained in the following way. On the extension 15, of each of the axles 13 is keyed a sprocket wheel 90 16. A chain 17 connects each sprocket wheel 16 with a stationary sprocket wheel 18, said stationary sprocket wheels 18 being advantageously supported in the brackets which journal the drive shaft 9. Obviously 95 the sprocket wheels 16 and 18 correspond in number, it being naturally irrelevant whether four separate and stationary sprocket wheels 18 or only one stationary wheel 18 having four sprocket rims are provided. 100

- The wheels 16 have double the number of sprockets in comparison with the sprockets of the wheels 18, the ratio of 2:1 thus offered insuring that in every revolution of the shaft 5 9, the sails 8 are rotated in an angle of 180°, as is clearly visible by the positions of the various sails 8 illustrated in Fig. 1 and as will be readily understood without further description.
- 10 The present invention further relates to an improved steering arrangement in connection with aerial ships. The terminal surface 19 (see Fig. 3) of the balloon body 3 is drawn in, producing thereby a conical or pyramid-shaped cavity. At the apex of the pyramid cavity is a semi-sphere socket 20 which affords a bearing for the conically pointed end 21 of a prismatic steering body 22. This steering body 22 is advantageously 15 hollow and fitted to receive a gas charge. It terminates at the rear also in a conically shaped end 23, in order to avoid the creation of a vacuum when the aerial ship is speedily propelled.
- 20 At the front portion of each of the four surfaces bordering the prismatic steering body 22, I attach a wire or rope. These four steering wires 24, 24, 25, 25 or ropes run to the car 11, being guided by suitably journaled pulleys 26 in such a manner that the prismatic steering member 22 may be turned in its universal joint socket 20 in horizontal as well as in vertical directions. It appears 25 advisable to run the topmost steering wire 25 along the upper surface of the balloon body 3 and down at the junction between the two chambers 1 and 3 through a tube 5 suitably provided whereupon it reaches the car 11. The ends of the two steering wires 24, 24 30 enabling the movement of the steering rudder 22 in horizontal directions as well as the ends of the two steering wires 25, 25 enabling the movement of the steering member in vertical directions are connected together.
- 35 The two endless straps thus formed are carried over and guided by pulleys 27, 28 in the car, being tensioned or held taut in any convenient manner. Cranks 29, 30 enable the pulleys 27, 28 respectively to be rotated, thereby causing the steering wires 24 or 25 40 to be moved and the steering rudder 22 to be turned upwards or downwards or laterally to right or left, according to whether the pulley 28 or 27 has been rotated.
- 45 The car 11 assumes, preferably, the shape of a small boat, terminating at both ends in wedges, to offer the smallest possible resistance to the air.
- 50 The source of motive power may be chosen as required by the prevailing circumstances. It appears however that either an internal combustion engine or an electro motor, driven from a suitable storage battery, is

best adapted for the purpose. The power transmission from the motor 10 to the shaft 65 9 is effected by a chain or belt gearing 31 or by a cogged wheel gearing as may be required.

The aerial ship hereinbefore described is fitted in the car with the customary aeronautical instruments, with the appliances facilitating the landing, with alimentary supplies and with other accessories providing comfort to the crew. If employed in war time for military purposes, it is stored with projectiles and with the means for projecting them downwards on the enemy.

The aerial ship so far as it concerns the balloon body is constructed of balloon silk stretched over suitable frames or it may be 80 composed of aluminium receptacles subdivided into a plurality of cells or chambers, each of which is filled with a gas charge. Should the external shell of the ship be injured, the last mentioned cellular construction of the aerial ship prevents fatal accidents by securing the gas charge of the unhurt cells or chambers against escape and enabling a safe landing when necessary.

I do not desire to be understood as limiting myself to the detail construction and arrangement of parts as herein shown and described, as it is manifest that variations and modifications therein may be resorted to, in the adaptation of my invention to 95 varying conditions of use, without departing from the spirit and scope of my invention and improvements. I therefore reserve the right to all such variation and modification as properly falls within the scope 100 of my invention and the terms of the following claims.

What I do claim as my invention, and desire to secure by Letters Patent, is:

1. An improved aerial ship comprising, in 105 combination, a two-part balloon body providing at the drawn in middle portion a space or chamber open towards the bottom but closed on top and at the sides; means for driving the aerial ship, consisting of a 110 paddle wheel whose sailing paddles perform a planetary motion during the rotation of the paddle wheel, housed in the aforesaid space or chamber and adapted to protrude therefrom at the lower end so as to engage 115 and act on the outer atmosphere; a car carried by the balloon body; a source of motive power arranged in the car; means of transmitting the power from the motor to the driving organs; means at the tail end of the 120 balloon body for steering the aerial ship consisting of a gas-holding prismatic body movable in horizontal and vertical directions; and means in the car for actuating the steering organ, substantially as described 125 and shown and for the purposes set forth.

2. An improved aerial ship of the nature set forth, having the balloon body provided with a pyramidalically drawn in tail end; a gas-holding prismatic steering member engaging the cavity at the tail end of the balloon body with its conical front portion and adapted to be turned therein in horizontal and vertical directions; and means in the car of the aerial ship for actuating the

steering member, substantially as described and shown and for the purpose set forth.

In witness whereof I have hereunto signed my name this 14th day of June 1907, in the presence of two subscribing witnesses.

FRANZ BOLLHORN.
